UNITED STATES PATENT OFFICE.

JOHN L. OSGOOD, OF BUFFALO, NEW YORK.

LATHE.

SPECIFICATION forming part of Letters Patent No. 707,155, dated August 19, 1902.

Application filed February 23, 1900. Serial No. 6,168. (No model.)

To all whom it may concern:

Be it known that I, JOHN L. OSGOOD, a citizen of the United States, residing at Buffalo, in the county of Erie and State of New York, 5 have invented certain new and useful Improvements in Lathes, of which the following is a specification.

The object of my invention is to increase the durability and life of lathes and similar 10 machines having guides upon which the carriages and other movable parts travel by providing the bed or frame of the lathe with grooves or channels in which separate or removable guides of hardened steel or similar 15 metal are fitted, the grooves or channels enclosing portions of the guides, and thus holding said guides rigidly in their proper position, all of which will be fully and clearly 20 hereinafter described and claimed, reference being had to the accompanying drawings, illustrating a preferred adaptation of my invention, in which—

Figure 1 represents a perspective view of a lathe provided with my improved guides. 25 Fig. 2 is an enlarged cross-section through a portion of a lathe to show the preferred adaptation of my invention. Fig. 3 is a detached perspective view of one form of my improved guide, showing a grooved rod which 30 is chiefly adapted to be fitted in a groove in the tailpiece or carriage of a lathe. Fig. 4 is a detached perspective view of another construction of my improved guide which may be made in sections or in entire lengths and 35 is chiefly adapted to be used as a bottom guide to be set in the lathe-bed.

In referring to the drawings in detail like numerals designate like parts.

I have shown a preferred form of my invention in the accompanying drawings embodied in a lathe, in which 1 designates the bed or frame thereof, 2 the head-block or carriage, and 3 the tailpieces.

The bed or frame is provided with parallel 45 grooves 4, which extend longitudinally throughout the entire length of the same.

The detachable rails 5 are formed of hardened steel or other metal and preferably with a slightly-tapered lower portion, so that they 50 can be seated rigidly in the grooves 4, which are correspondingly tapered. (See Fig. 2.)

The head-block or carriage and the tail-piece instead of having the usual grooves formed therein to receive the rails may have grooves 6, circular in cross-section, in which 55 detachable rods 7, of hardened metal, are fitted, said rods having grooves 8, in which the projecting portions of the rails extend and fit, thereby correspondingly increasing the durability of these portions of the lathe. 60

In Fig. 1 four rails and four grooved rods are shown, but more or less may be used. They may be inverted or otherwise changed in form, or the upper grooved rods in some instances may be dispensed with. 65

The chief advantages of my invention are in the great increase in the durability, life, and maintenance of accuracy of the machine.

Owing to the hardness of the metal in my improved guides the dropping of tools or 70 other heavy articles upon the projecting rails, which frequently occurs during the operation of the machine, will not perceptibly dent or mar the surface of the guides. The rails and the grooved rods are held very firmly and 75 rigidly in position and cannot vibrate independently or become distorted from use or abuse, as a portion of each rail is sunk or embedded in grooves or depressions in that part of the machine to which it is attached throughout the entire length, the metal of the lathe 80 part partly surrounding and strengthening the rail or rod and the rail or rod in turn strengthening the lathe.

In preparing my improved guides I first cut 85 the proper length and the proper size in cross-section, then harden by rolling, hammering, or tempering, and finally grind the surface down by any suitable means to remove any distortion, thereby forming an absolutely true 90 guide of sufficient hardness to prevent indentations by any ordinary means, such as the dropping of a tool or other metal being worked thereon.

My improved guide when rigidly set in position in the lathe forms a part of the same 95 and serves not only as a guide of harder and stronger metal than that heretofore employed, but also as an independent detachable strengthening-rib for the lathe of harder, 100 more condensed, and stronger metal. The friction is appreciably lessened and wear is

substantially prevented, owing to the smoothness and hardness of the contacting surfaces of my improved guides.

I claim as my invention—

- 5 1. In a lathe, a bed or frame having grooves, rails of hardened metal fitted in said grooves and having portions extending above the surface of the bed, a carriage having grooves on its under surface, rods of hardened metal fitted in said grooves and having depressions in which the extensions of the rails project.
- 10 2. In a lathe, a bed or frame having grooves, rails of hardened metal fitted in said grooves and having portions extending above the surface of the bed, a carriage having grooves on its under surface semicircular in cross-sec-
- 15

tion, rods of hardened metal fitted in said grooves and corresponding in form to the semicircular cross-section of the groove; said rods having bottom depressions in which the extensions of the rails project.

3. In a lathe, a bed or frame having grooves, rails of hardened, tempered and true-ground metal fitted in said grooves, and having portions extending above the surface of the frame and a carriage having grooves on the under surface in which the extensions of the rails project.

JOHN L. OSGOOD.
